DESIGN.

J. Q. REED.

LADY'S COSTUME.

No. 15,150.

Patented July 15, 1884.

UNITED STATES PATENT OFFICE.

JOHN QUINCY REED, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,150, dated July 15, 1884.

Application filed May 23, 1884. Term of patent 3½ years.

To all whom it may concern:

Be it known that I, JOHN QUINCY REED, of the city, county, and State of New York, have invented and produced a new and original Design for a Pattern of a Lady's Costume, (numbered 9,281;) and I do hereby declare that the engraved prints accompanying this specification convey to any one accustomed to using paper patterns a clear understanding of how a garment made up by the pattern will appear.

The design shows a walking-skirt and a round waist. The skirt exhibits a deep front-drapery that displays a short shirring near the bottom at the right side of the center, and shapes a deep point at the right side and a rounding outline toward the left side, and a deep, rounding back-drapery exhibiting drap-

ing plaits in its front edges and loopings at the center. The waist discloses a fitted, high-necked upper portion displaying a closing at the back, and a full, low-necked lower portion, also displaying a closing at the back, and exhibiting shirrings across the center of the front and back a little below the neck and at the waist-line; coat-sleeves, and a standing collar.

What I claim as my invention, and desire to secure by Letters Patent, is—

The design for a lady's costume, as shown in the engraved prints accompanying this specification.

JOHN QUINCY REED.
